(57) **CLAIM**

The ornamental design for a barrel as shown and described.

DESCRIPTION

FIG. 1 is a perspective view of a barrel, showing the new design.

FIG. 2 is a right side view thereof;

FIG. 3 is a left side view thereof;

FIG. 4 is a front side view thereof;

FIG. 5 is a back side view thereof;

FIG. 6 is a top view thereof;

FIG. 7 is a bottom view thereof;

FIG. 8 is a perspective view of a barrel, shown in an alternate configuration;

FIG. 9 is a left side view thereof;

FIG. 10 is a right side view thereof;

FIG. 11 is a front side view thereof;

FIG. 12 is a back side view thereof;

FIG. 13 is a top view thereof; and,

FIG. 14 is a bottom view thereof.

The broken lines in the drawings illustrate portions of the barrel that form no part of the claimed design.

1 Claim, 14 Drawing Sheets
